(57) **CLAIM**

The ornamental design for a surgical curette, as shown and described.

DESCRIPTION

1. Surgical curette

1.1 : Perspective

1.2 : Front

1.3 : Back

1.4 : Left

1.5 : Right

1.6 : Top

1.7 : Bottom

This design is characterized in the combination of shape and form of surgical curette where the working end of the surgical curette as shown in solid line forms part of the claimed design, while the portion of the surgical curette as shown in dotted line does not form part of the claimed design; the designed surgical curette can be used for arthroscopy of knee and ankle, etc.
